US0D1054430S

(12) **United States Design Patent** (10) Patent No.: **US D1,054,430 S**
Ellison et al. (45) Date of Patent: ** Dec. 17, 2024

(54) **DISPLAY SCREEN WITH GRAPHICAL USER INTERFACE**

(71) Applicant: **Walmart Apollo, LLC**, Bentonville, AR (US)

(72) Inventors: **Benjamin R. Ellison**, San Francisco, CA (US); **Ravi Kumar Dalal**, Dallas, TX (US)

(73) Assignee: **Walmart Apollo, LLC**, Bentonville, AR (US)

(**) Term: **15 Years**

(21) Appl. No.: **29/772,546**

(22) Filed: **Mar. 2, 2021**

(51) LOC (14) Cl. **14-04**

(52) U.S. Cl.

(57) **CLAIM**

The ornamental design for a display screen with graphical user interface, as shown and described.

DESCRIPTION

The FIGURE is a front view of display screen with graphical user interface.

The outermost broken line depicts an electronic device and forms no part of the claimed design. The solid line rectangle depicts a display screen and forms part of the claimed design. The remaining broken lines depict portions of the graphical user interface and form no part of the claimed design.
